UNITED STATES PATENT OFFICE

ROY MEADER, OF SPRINGFIELD, MASSACHUSETTS, ASSIGNOR TO THE A. NASH COMPANY,
OF CINCINNATI, OHIO, A CORPORATION OF OHIO

DISPLAY DEVICE

Application filed September 3, 1931. Serial No. 561,011.

This invention relates to a device for displaying cloth or fabric.

An object of the invention is to provide a device which may be readily attached to 5 and detached from a supporting member and which is designed to hold a section of cloth in such a way and at such an angle that an impression may be gained of the appearance of the cloth as it would be in a finished article 10 of wearing apparel.

Another object is to provide a device of the kind described which is free of sharp projecting parts which might injure the cloth held thereby.

15 Another object is to provide a display device the attachment part of which may be applied to other display boards and to other similar devices.

Another object is to produce a simple and 20 efficient article of the class described at a minimum of cost. These and other objects are attained by the means described herein and set forth in the accompanying drawing, in which:

25 Fig. 1 is a rear elevational view of the display board of the present invention.

Fig. 2 is a front elevational view of the same.

Fig. 3 is a cross sectional view taken on line 30 3—3 of Fig. 1.

Fig. 4 is a side elevational view of two of the devices of this invention supported adjacent to a wall in a manner in which the devices are preferably utilized for display 35 purposes.

The present device is adapted to overcome the disadvantages of previous similar display means the use of which entailed considerable wrinkling of the fabrics displayed thereon. In such previous devices it has been necessary to gather or bunch the material at the rear of some supporting device, a common type of which was provided with a central column or standard upon which the display board was attached, and around which the material was tied or otherwise fastened. A still commoner method has been to simply drape large portions of the fabric over some suitable rack positioned upon a 40 table or the like. These and similar methods

not only resulted in wrinkling and soiling of the materials displayed but likewise required considerable space. In order to overcome these and similar disadvantages the present invention provides a single elongated display board having an attachment means at its upper end and adapted to be slipped over the top edge of a support bar or board attached to and offset from a wall. The board is adapted to be covered with a limited amount 55 of fabric but nevertheless sufficient to give an impression of the material as it might appear in the finished article. The devices when attached extend angularly from the wall surface so that the light is received at a 60 favorable angle. Due to the fact that the material is attached in a flat condition, no wrinkling results. Moreover, due to the shape of the display board and to the type of 65 supporting means, the devices of this invention may be positioned side by side in a great number and in a double row along the wall, so that by their use considerable space-saving is effected.

With reference to the drawing: the device 75 of the present invention comprises an elongated smooth board 5 which has its edges, corners, and surfaces suitably smoothed to prevent injury to the fabrics attached to the board. The front face 6 of the board is entirely plain and smooth. The rear face 7 of the board is provided with an attachment clamp 8. This member is preferably formed of a resilient metal strip formed to provide a top flange 9 beneath which the metal is 80 given a U-shaped bend to provide the flange portion 10. Thereafter the strip is straightened out into spaced parallelism with the flange 9, this elongated portion 11 and the clamp flange 9 being disposed at an angle to 85 the portion 10. The metal strip is further bent as at 12, carried backwardly and bent again as at 13 to provide the bottom flange 14 which lies in the same plane as the top portion 10. A filler block 15 is adapted to be 90 placed within the large opening of the clamp member thus formed, the rear edge 16 of the filler block being disposed in the same plane as the flange 14 and the portion 10 of the flange. Suitable securing means such 95 100

as the nail 17 may be used to retain the filler block in place.

The clamp member 8 is attached to the central portion at the top of one face of the board 5. For this purpose the portion 10, flange 14, and rear edge 16 of the filler block 15 are placed against the face of the board and secured in position by means of screws 18 passing through perforations provided in 10 the portion 10 and flange 14 of the clamp.

It will be seen by reference to Fig. 4 that the device of this invention is adapted to be positioned upon horizontally extending boards 19 attached to supporting wall 20. 15 The uppermost of the boards 19 is only slightly spaced from the wall while the lowermost of the boards is spaced outwardly by use of a suitable extension piece 21. In positioning the display board of this invention, the top 20 edge of the device is slidably positioned upon the top edge of the supporting boards 19, at which time the flange 9 lies flush against the rear face of the supporting board and the elongated portion 11 lies flush against the 25 outer face of the supporting board. Inasmuch as the greatest weight of the device is disposed below the clamp, a sufficient lever- 30 age action to insure proper positioning is operative upon the flange 9 and the portion 11 of the clamp. The display device thus positioned projects outwardly in the manner shown in Fig. 4. It will likewise be seen that in the preferable positioning of the device, the tops of the lowermost row of display 35 boards extend outwardly beyond the bottom edge of the row above. In this way an attractive and space-saving arrangement is effected. The dotted lines in Fig. 4 indicate a desirable way of draping fabric upon the 40 display device. A section of the fabric is stretched over the front face 6 of the board 5 and allowed to hang downwardly below the display board so that an extensive view of the fabric may be obtained. The fabric 45 may be attached to the board in any suitable way, such as by the use of thumb tacks. All gathering and wrinkling of the fabric is avoided. It is apparent that should a customer desire to handle the selected piece of 50 material, the display device may be instantly removed from place, and as readily returned when desired. It is further obvious that 55 the clamp member 8 may be used upon display boards of different sizes and likewise upon other articles which it may be desirable to position in a manner similar to the article of this invention.

What is claimed is:

1. A device for displaying fabrics and 60 adapted to be positioned upon the top edge of a horizontal supporting strip disposed vertically as to its width, said device comprising a fabric-holding board and an attachment member secured to one face of the board at 65 the top thereof and formed of a metal strip

bent to provide a clamp portion adapted to slidably engage the top edge of the supporting strip, and an elongated portion adapted to bear against the front face of the supporting strip, said clamp and elongated portions being parallel and projecting downwardly and outwardly of the board for holding the board, during operative condition of the device, in a similar position relative to the supporting strip. 75

2. A device for displaying fabrics and adapted to be positioned upon the top edge of a horizontal supporting strip disposed vertically as to its width, said device comprising a fabric-holding board and an attachment member secured to one face of the board at the top thereof and providing a clamp portion adapted to slidably engage the top edge of the supporting strip and an abutment portion disposed angularly relative to the board and adapted to abut the front face of the supporting strip for holding the fabric-holding board at a similar angle relative to said strip. 80

3. A device for displaying fabrics and adapted to be positioned upon the top edge of a horizontal supporting strip disposed vertically as to its width, said device comprising a fabric-holding board and an attachment member secured to one face of the board at the top thereof and consisting of a metal strip 95 bent at each end to provide an angularly-extending portion terminating in a flange, said extending portions being of unequal length and said flanges being perforated and adapted to be disposed in a common plane, the metal strip being further bent, beyond the flange of the shorter extending portion, to provide a clamp flange projecting beyond and overhanging the body portion of the metal strip in parallel relation therewith and disposed upon the side opposite said aforementioned flanges, the attachment member so formed being adapted to be fastened to said board by securing means passing through said perforated flanges, and the clamp formed by said clamp flange and the intermediate portion of the metal strip being adapted to engage the top edge of said supporting strip for holding said board in a downwardly projecting angular position relative to the 105 supporting strip. 110

4. As a new article of manufacture, a clamp adapted for use upon an upright supporting member having an upwardly-facing free edge, said clamp being formed of a metal strip bent to provide angularly-extending portions of unequal lengths and projecting in the same direction, said portions being each bent outwardly to form a pair of flanges adapted to be disposed in a common plane, 125 the strip beyond the flange of the shorter extending portion, being bent oppositely to said portion and formed at the end to provide a clamp flange overhanging and in spaced relation with the body portion of the strip, said 130

5 clamp flange being adapted to engage the rear and the strip body the front of an upwardly-facing edge portion of the upright supporting member for holding said out-bent flanges in a plane extending downwardly at an angle to the plane of the supporting member, and means for securing an object to said out-bent flanges whereby the object may be held at an angle to the supporting member.

10 5. As a new article of manufacture, a clamp adapted for use upon an upright support board, said clamp comprising a metal strip bent to provide two angularly-extending portions of unequal length and projecting in the same direction, means for attaching an object to the projecting ends of said extending portions, and a flanged member projecting from said strip adjacent and in an opposite direction to the shorter of said extending portions, the flange of said member and said strip being adapted to slidably engage between them an upper edge portion of said support board for holding at an angle to said board the object held by said extending portions.

25 In testimony whereof, I have hereunto subscribed my name this 29th day of August, 1931.

ROY MEADER.
